UNITED STATES PATENT OFFICE

RAYMOND LOEWY, OF NEW YORK, N. Y., ASSIGNOR TO HUPP MOTOR CAR CORPORATION,
OF DETROIT, MICHIGAN, A CORPORATION OF VIRGINIA

DESIGN FOR A HUB CAP

Application filed June 1, 1931. Serial No. 40,043. Term of patent 7 years.

To all whom it may concern:

Be it known that I, RAYMOND LOEWY, a citizen of the Republic of France, residing at New York, in the county of New York and State of New York, have invented a certain new, original, and ornamental Design for a Hub Cap, of which the following is a specification, reference being had therein to the accompanying drawings, forming a part thereof, wherein:

Figure 1 is a front elevational view of a hub cap showing my new design;

Figure 2 is an end elevational view of the cap shown in Figure 1; and

Figure 3 is a side elevational view of the cap illustrated in Figure 1.

I claim:

The ornamental design for a hub cap substantially as shown.

RAYMOND LOEWY.
